DUPLICATING BAND

Johan Bjorksten, Chicago, Ill., assignor to Ditto,
Incorporated, Chicago, Ill., a corporation of
West Virginia

Application January 31, 1938, Serial No. 187,810

3 Claims. (Cl. 41—31.6)

The invention relates to hectograph pads, bands or rolls which usually comprise a flexible backing member having a coating of gelatinous material to which the master sheets are first applied and to which the copy sheets are subsequently applied to duplicate data or designs received by the gelatinous material from the master sheets.

It has been the general practice to provide backing sheets of organic origin, such as, for example, papers or textile fabrics. Among the disadvantages inherent in such material are greatly decreased mechanical strength when wet, lack of uniformity in strength, great sensitivity to atmospheric conditions, particularly humidity, necessity of highly complex and time consuming treatments, high inflammability, and, where a drying oil is used as an agent for bonding the gelatinous mass to the backing sheet, danger of self-ignition.

The invention contemplates a hectograph blanket or roll comprising a flexible backing sheet of inorganic material not having the above enumerated disadvantages.

Several forms of the invention are embodied in hectograph rolls or bands which employ a thin flexible metal sheet as a backing. The backing sheet is preferably aluminum and is preferably .002 inch thick. The gelatinous mass is secured to the backing sheet by a bonding agent which may also contain dye absorbing agents to clear the gelatinous mass. If so desired, the bonding agents and the dye absorbing agents may be applied as separate films or coatings to the backing sheet. In some instances, the metallic backing sheets have their edges folded to prevent tearing thereof. The backing sheets may also be corrugated to add to their strength.

Other objects and advantages will become apparent as the following detailed description progresses, reference being had to the accompanying drawing, wherein Figs. 1 to 6, inclusive, are fragmentary perspective views of hectograph bands which embody different forms of the invention.

Referring for the present to Fig. 1 wherein a preferred embodiment of the invention is illustrated, the reference character 11 designates a backing sheet of a hectograph band which is designated generally by the reference character 10. The backing sheet 11 is preferably formed of aluminum and is preferably about .002 inch thick. Applied to one surface of the backing sheet 11 is a coating or film 12 which forms a bonding agent to cause a gelatinous coating 13 to be bonded to

the backing sheet 11. The gelatinous coating 13 is preferably of the type commonly employed in the hectograph process. The film or coating 12 preferably is or comprises a protein precipitant capable of adhering to the metal surface. Such coatings are, for example, fish oil, linseed oil and cellulose lacquers containing protein precipitants such as, for example, formaldehyde, aldol or chromalum. To increase the clearing properties of the film or coating 12, it also contains preferably dye absorbing agents in solution or suspension, or it may be superimposed on a film of such dye absorbing or neutralizing agents. Such dye absorbers are, for example, many colloids such as cellulose derivatives, resins, particularly when plasticized with dye solvents, silica gel, bentonite, ground wood pulp, wood powder and the like. These dye absorbers or neutralizers will assist in clearing the duplicating film after use, by binding and thus removing dyestuffs from the film.

The back side of the backing sheet 11 is preferably coated with a film 15 of dye removing agents, such as described above, which agents will assist in removing the dye from the duplicating film against the surface of which the back side of the 25 backing is pressed when the hectograph band 10 is wound into a roll.

Referring now to Fig. 2 wherein another embodiment of the invention is disclosed, the reference character 20 designates generally a hectograph band which comprises a backing sheet 21 preferably formed of aluminum about .002 inch thick. Applied to the opposite sides of the backing sheet 21 are coatings or films 22 and 23 which preferably comprise dye removing agents of the 30 type described above. Applied to the film or coating 22 is a film or coating 24 for bonding a gelatinous coating 25 to the backing sheet 21. The bonding coating 24 preferably comprises protein precipitants as defined above. Of course, 40 the films 24 and 22 may be permitted to intermingle so that the final result is substantially the same as that described in connection with Fig. 1 wherein the coating 12 contains both bonding and dye removing agents.

Referring now to Fig. 3 wherein another form of the invention is illustrated, the reference character 30 designates generally a hectograph band which comprises a gelatinous coating 35 of the type usually employed in the hectograph process. 50 The gelatinous coating 35 is bonded to a backing sheet 31 which is preferably formed from aluminum about .002 inch thick. The backing sheet 31 is preferably in the form of a perforate sheet having a plurality of relatively large perforations 31a 55

therein. A coating 32 interposed between the backing sheet 31 and the gelatinous material 35 preferably comprises the same materials as the coating or film 12 described above so that it not only bonds the gelatin to the backing sheet, but also absorbs dyestuffs and assists in clearing the duplicating film after use.

Another form of the invention is illustrated in Fig. 4 wherein a fragmentary portion of a hectograph band 40 is shown. The hectograph band 40 comprises a backing sheet 41 which is formed from metal, preferably aluminum, the sheet being preferably about .002 inch thick. The backing sheet 40 is preferably provided with a plurality of corrugations 41a extending transversely thereof to strengthen the sheet. Applied to one surface of the backing sheet 41 is a coating 42 which preferably comprises the same materials as the coating 12 described above and has the same functions. The coating 42 bonds a gelatin coating 45 to the backing sheet 41 and as it preferably contains dye absorbing agents, it assists in clearing the gelatinous mass after use.

Fig. 5 illustrates still another form of the invention. The reference character 50 designates generally a hectograph band of which a portion is shown in Fig. 5. The hectograph band 50 comprises a backing sheet 51 which is formed of metal, preferably aluminum, the sheet being preferably about .002 inch thick. The longitudinal edges of the backing sheet 51 are folded as indicated at 52 in Fig. 5 to give strength to the longitudinal edges so that they will not tear readily. Applied to the backing sheet 51 is a coating 52 which is preferably formed from the same materials as the coating 12 described above and has the same functions. The coating 52 bonds a gelatinous coating 53 to the backing sheet 51 and the dye absorbing agents in the coating 52 assist in clearing the gelatine after it has been used in the hectograph process.

In Fig. 6, a form of the invention is shown in a hectograph band 60 which comprises a metallic backing member 61 and a gelatin film or coating 64 of the type commonly employed in hectograph bands. The backing member 61 is preferably a mesh or screen which may be formed from thin metallic ribbons or may be formed as a wire mesh, the mesh being flattened as by rolls to flatten the individual wires. A coating 62 is applied to at least one side of the mesh, that is the side to which the gelatin coating 64 is applied. The film or coating 62 is preferably formed of the same materials as the coating 12 described above and bonds the gelatin 64 to the mesh. The dye absorbing materials in the coating 62 assist in clearing the gelatinous mass 64 after it has been used.

The mesh 61, if formed from ribbons, is preferably formed from thin aluminum strips.

An advantage of bonding metallic backing sheets of the kind described is that it may be

subjected to high temperature without injury while in the use of paper or cloth backing sheets, care must be taken so that they will not be injured by high temperatures when they are coated with lacquers, etc., and the lacquer is 5 dried by subjecting it to heat.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the 15 prior art.

I claim:

1. In a hectograph band capable of being wound into a roll, the combination of a thin flexible backing sheet of non-absorbent material, coating means covering one face of said backing sheet and comprising an effective proportion of dye absorbent material for expediting the clearing of the band for repeated use, and a layer of gelatinous material bonded effectively to said first-named coating and of comparatively much greater thickness than that of the backing sheet which is made of substantially the minimum thickness consistent with the required strength.

2. In a hectograph band capable of being wound into a roll, the combination of a thin flexible backing sheet of non-absorbent material, coating means covering one face of said backing sheet and comprising an effective proportion of dye absorbent material for expediting the clearing of the band for repeated use, a hectograph copy mass bonded effectively to said first-named coating and a coating covering the other face of said backing sheet and comprising an effective proportion of dye absorbent material for assisting in the clearing operation preparatory for a repeated use of the band.

3. In a hectograph band capable of being wound into a roll, the combination of a thin flexible backing sheet of aluminum, coatings covering both faces of said backing sheet each comprising an effective proportion of dye absorbent material, a third coating covering one of said first-named two coatings and comprising an effective proportion of protein precipitant material adapted effectively to bond said second coating to the face of the metal backing sheet so as to permit flexing of the completed band on a comparatively small radius without danger of breaking the bond, and a coating of gelatinous material bonded effectively to said third coating and of comparatively much greater thickness than that of the backing sheet which is made of substantially the minimum thickness consistent with the required strength.

JOHAN BJORKSTEN.
